RUDOLF GOLDSCHMIDT, OF DARMSTADT, GERMANY.

APPARATUS FOR AND METHOD OF RECEIVING ELECTRIC WAVES.

1,104,256.

Specification of Letters Patent.

Patented July 21, 1914.

Application filed March 29, 1911. Serial No. 617,735.

To all whom it may concern:

Be it known that I, RUDOLF GOLDSCHMIDT, a subject of the Grand Duke of Hesse, and residing at Darmstadt, in the Grand Duchy 5 of Hesse, German Empire, have invented certain new and useful Improvements in Apparatus for and Method of Receiving Electric Waves, of which the following is a specification.

10 The frequency of the waves employed for wireless telegraphy and telephony is too great to be directly perceived in the receivers.

15 The object of the present invention consists in diminishing the frequency of the waves in such a degree that they become capable of being directly perceived in a telephone, or of actuating other apparatus.

In the accompanying drawing: Figure 1 20 is a diagrammatic view of a frequency-diminishing apparatus embodying my invention; Fig. 2 a diagram of a modification showing two machines in cascade-connection; Fig. 3 a diagram of a further modification, showing the electrical energy conducted back from the stator to the rotor etc.; Fig. 4 a diagram of a still further modification showing the rotor and stator employed respectively as primary and secondary 25 parts, and Fig. 5 a diagram of another modification showing both the primary and secondary parts made rotatable.

The current coming from the antenna A 30 and passing down to the earth E (directly or by the mediation of transforming intermediate circuits with loose or fast coupling) is conducted into the stator-coil S, whereas the rotor R preferably lies in a short-circuit with a condenser C serving for regulating or 35 "pitching" purposes. The receiver T of any suitable construction is inserted into the rotor-circuit, if desired, in connection with an intermediate circuit. If the receiver is actuated from the motor in such a manner 40 that the transformation of frequency before mentioned occurs, then the frequency of the motor-currents, which corresponds to the "slip," may be so chosen that a musical sound is produced within the telephone.

45 The wiring need not, of course, be such a one that the whole current passes through the receiver. When constructing such a detector, similar difficulties are encountered as are inherent in generators of high frequency for 50 the reason that the high frequency of the currents employed in wireless telegraphy

and telephony requires a high velocity of the rotor. Today, about 30000 periods (waves of 10000 meters length) represent the lowest frequency employed in wireless 60 telegraphy. Now, in order to produce, for instance, a sound easily perceptible within a telephone, the 30000 periods must be changed to 500 periods, and in order to bring about this low frequency within the 65 rotor, the speed of the latter ought to differ from the synchronous speed only by

$$\pm \frac{500}{30000} = 1.67\%$$

(that means a slip of 1.67%); in other 70 words, the speed of the motor must be nearly the synchronous one. The receiving machine should therefore be constructed similar to a high-frequency generator. With a detector, however, circumstances are somewhat 75 simpler, because the effect of the machine need be but small.

The chief advantage of the induction-machine when used as detector resides in the fact that not, as with a ticker, the ticking-noise is heard, but there is heard a sound or tone which depends upon the wave-length itself. Suppose the number of rotations be such, that at 30000 periods (10000 meters wave-length) a tone of 500 oscillations per 80 second is produced, then another wave that differs from the former only by 1% (9900 meters, corresponding to 30300 periods) 85 would cause a tone of 800 oscillations, the pitch of which would thus differ by 60% 90 from that produced by the wave of 10000 meters length. The peculiar behavior of the asynchronous detector to annunciate the difference between the frequency of the arriving wave and that of its own number of 95 rotations in the form of a tone makes this detector particularly adapted to obtain a greater freedom from disturbances by other stations, as well as from atmospheric disturbances in case the antenna be but 100 slightly out of pitch. Another essential advantage consists in this, that the same machine may be employed as sending instrument in lieu of as receiving instrument, in which case the machine is used as asynchronous generator shown to be driven by a 105 belt B.

In certain instances, it may be advantageous to replace the single machine above described by a plurality of machines in 110 cascade connection, two of such machines being illustrated in Fig. 2. Furthermore,

the number of rotations of a single machine may be reduced by stepwise returning the electrical energy from the stator to the rotor, from the latter to the stator, and so on, as 5 illustrated in Fig. 3. For this purpose, the slip rings of rotor R are by wires *a*, *b* not only connected to the rotor winding but also to the wires *c*, *d* that respectively connect the stator winding to the antenna A and 10 ground E, condensers C' being provided for wires *a*, *b*. The speed reduction above referred to is here due to the fact that by returning the energy, the slip may be increased. In other words, the receiver is not 15 supplied with the current, which is caused by the slip of the rotor relatively to the primary periodicity of the energy supplied to the stator but by returning the current to the rotor, the primary current of high frequency 20 is superimposed upon the current of the meanwhile reduced slip frequency. In this way, the receiver is supplied with a current generated by said slip relatively to the second stator current. It may also be de- 25 sirable in certain cases, to have the stator and rotor exchange their rôle as primary and secondary part (Fig. 4); or both, the primary and the secondary part may be rotated (Fig. 5). 30 Having now described my invention, what I desire to secure by a patent of the United States is:

1: In wireless signaling, means for intercepting the energy of high frequency elec- 35 tromagnetic waves radiated through the at-

mosphere, a receiving instrument adapted to be operated by low frequency alternating current having a constant amplitude, and means for transforming the intercepted high frequency current into such low frequency 40 current of constant amplitude.

2. Apparatus of the character described, comprising an asynchronous transformer adapted to reduce the frequency of intercepted electric waves, and a receiver to which 45 the waves of reduced frequency are conducted.

3. Apparatus of the character described comprising an antenna adapted to intercept electric waves of high frequency, an 50 asynchronous transformer, means for conducting said waves from the antenna to said transformer, and means for receiving the transformed waves from the transformer to render them perceptible.

4. In wireless signaling, the method of receiving messages, which consists in intercepting the energy of high frequency electromagnetic waves radiated through the atmosphere, and transforming said intercepted 60 current into low frequency alternating current, whereby the intercepted high frequency current is translated into a current that is readily perceptible.

In testimony whereof I affix my signature in presence of two witnesses.

RUDOLF GOLDSCHMIDT.
